UNITED STATES PATENT OFFICE.

HARRY FARBER AND LOUIS FARBER, OF NEW YORK, N. Y.

DESIGN FOR A FRUIT-BOWL.

56,861.

Specification for Design.

Patented Jan. 4, 1921.

Application filed July 9, 1920. Serial No. 395,154. Term of patent 3½ years.

To all whom it may concern:

Be it known that we, HARRY FARBER and LOUIS FARBER, citizens of the United States, residing at New York, in the county of New York and State of New York, have invented a new, original, and ornamental Design for Fruit-Bowls, of which the following is a specification, reference being had to the accompanying drawing, forming part thereof.

In the drawing:—

Figure 1, is a plan view of the fruit bowl.
Fig. 2, is a side elevational view of the same.

We claim:—

The ornamental design for a fruit bowl, as shown.

HARRY FARBER.
LOUIS FARBER.
